VARIABLE TYPEWRITER SPACER

Martin R. Chambers, Milton, N. C.

Application May 11, 1948, Serial No. 26,403

5 Claims. (Cl. 197—84)

1

This invention relates to typewriters, and more particularly to means for providing escapement of the carriage of a typewriter to meet the spacing or width requirements of each letter, character, punctuation mark, blank space, or the like, as in ordinary printing.

A prime purpose of the present invention is to provide a typewriter mechanism of particular use in such operations as preparing copy for duplication by stencil or hectograph process, for direct printing, on metal or paper plates, or for photo-offset printing. Heretofore, typewriters have been principally a substitute for writing. The present invention contemplates a machine which is in addition an automatic printer, in that its copy can be used directly for making plates from which books or periodicals may be printed, without the necessity of setting up type.

A main object of the invention is to provide a novel and improved spacing mechanism for typewriters whereby letters and characters on the typewritten page may be spaced longitudinally in substantially the same manner as in ordinary printing instead of being spaced by a single standard distance for all letters, characters and spaces as in conventional typewriters.

A further object of the invention is to provide an improved spacing mechanism for typewriters wherein variations in the space requirements for different letters and characters are taken into consideration, as is done in ordinary printing, and means is provided in the mechanism for giving each letter or character its required space along the printed line of the paper instead of employing a single standardized space as is done in conventional typewriters, whereby the typed page is neater in appearance, more legible and is more economical in the utilization of space on the sheet, than in the case of the typewriters now in current use.

A still further object of the invention is to provide an improved typewriter spacing mechanism wherein variation of spacing of characters and letters may be obtained as required for the respective letters and characters in the same manner as in printing and wherein provision is made for employing the same mechanism with different styles of type, the arrangement of the mechanism being such that more space is allowed for wide characters, letters and capitals than for narrow letters and for characters of narrow width, and wherein the spacing between words may likewise be regulated as desired.

Further objects and advantages of the invention will become apparent from the following de-

2

scription and claims, and from the accompanying drawings, wherein:

Figure 1 is a top plan view, partly broken away, of a typewriter provided with variable spacing mechanism in accordance with the present invention.

Figure 2 is a transverse vertical cross-sectional view taken through the typewriter of Figure 1.

Figure 3 is an enlarged cross-sectional detail view taken on line 3—3 of Figure 1.

Figure 4 is an enlarged detail view, partly in cross-section, of a portion of the ratchet wheel controlling movement of the carriage of the typewriter of Figure 1 and an adjacent portion of the escapement bar cooperating with said ratchet wheel, the bar being shown in disengaged position with respect to the wheel, as when a key of the typewriter is depressed.

Figure 5 is an enlarged fragmentary elevational detail view of the ratchet wheel and escapement bar of the typewriter of Figure 1, showing the actuating elements for operating the escapement bar.

Figure 6 is a cross-sectional detail view taken on line 6—6 of Figure 5.

Figure 7 is a fragmentary perspective detail view of spacing levers employed in the typewriter of Figure 1 in conjunction with the spacer bars thereof.

Referring to the drawings, 11 designates the frame of the typewriter, said frame being conventional in form and having a rear wall portion 12, side walls 13 and 14, a front wall portion 15, a bottom wall portion 16, and a forwardly extending yoke portion 17 defining the space for the typewriter keyboard. The platen is designated at 18 and is rotatably mounted on a longitudinally movable carriage 19 which carries a suitable frame to which is secured a longitudinal rack bar 20 rearwardly spaced from the platen 18 and parallel thereto, the teeth of the rack bar 20 being directed forwardly and downwardly, as shown in Figure 2.

Rotatably mounted in the rear portion of the frame 11 forwardly of rack bar 20 is a vertical shaft 21 which carries at its top end a bevel gear 22 meshing with rack bar 20. Secured to the bottom wall 16 of housing 11 around the lower end of shaft 21 is a cylindrical housing 23 containing a spiral spring 24. The inner end of spring 24 is secured to shaft 21 and the outer end thereof is secured to the cylindrical wall of housing 23, whereby the shaft 21 and bevel gear 22 are biased in a counter-clockwise direction, as viewed

in Figure 1, when the spring is tensioned. Due to

the meshing engagement of bevel gear 22 with rack bar 20, carriage 19 is therefore urged to the left when shaft 21 is released.

Secured to the intermediate portion of shaft 21 is a ratchet wheel 25. Engaging the periphery of ratchet wheel 25 and normally interlocking therewith to hold said wheel against rotation is a ratchet bar 26. Ratchet bar 26 is pivotally secured at its forward end as shown at 27 to a rearwardly projecting arm 28 carried by a longitudinal bar member 29. At the ends of bar member 29 are arms 34, 34 which are pivotally connected to the type-arm assembly block 42, said arms being connected by springs 30, 30 to rearwardly adjacent lugs 31 projecting inwardly from the side walls 13 and 14, whereby bar member 29 is biased rearwardly. Rack bar 26 is normally maintained in engagement with ratchet wheel 25 by a flat spring 32 secured to arm 28 and bearing on bar 26 to urge it counter-clockwise, as viewed in Figure 1. Bar 26 is biased into abutment with rear wall 12 by the axial rearward force exerted thereon by arm 28. Flat spring 32, in cooperation with the contour of the teeth on ratchet wheel 25 and rack bar 26, permits free manual return of the carriage to the right.

Bar 26 has a vertical depending flange 33 formed with inwardly extending ratchet teeth 35 which are opposite in contour to but the same size as the main ratchet teeth indicated at 36, of the bar. Said main ratchet teeth 36 normally interlock with the ratchet teeth of wheel 25 and said wheel is held against counter-clockwise rotation by the abutment of the end of bar member 26 against rear wall 12.

The typewriter keys are designated at 37, each key being carried at the forward end of a lever 38 pivoted on a longitudinal rod 39 carried by the typewriter frame adjacent the rear wall 12. Each lever 38 is biased upwardly by a spring 40 connecting it to an upwardly adjacent portion of the front wall of the housing. The position of spring 40 is optional, depending upon the make of the typewriter. Each lever has an intermediate upwardly projecting arm 41 to the top end of which is pivoted in a conventional manner a type-carrying arm 42. Whenever a key 37 is depressed the lever 38 thereof is rotated counter-clockwise, as viewed in Figure 2, and the type-carrying arm 42 thereof is rotated clockwise into striking engagement with the platen 18 by conventional means such as the link 42' connected between the key lever arm 41 and the type-carrying arm 42.

Designated at 43 is a longitudinal bar member underlying the key levers 38, which are all normally disposed in a common horizontal plane, said bar member 43 having end arms 44 pivoted at their ends to the bottom wall of the frame 11, as shown at 45. Designated at 47 is a lever slidably and pivotally connected at 48 to an upstanding projection 49 rising from bottom wall 16. The forward end of lever 47 underlies the bar member 43. The rear end of lever 47 has pivotally connected thereto an upstanding arm 50. Secured beneath the forward end of lever 47 is a spring 46 which biases said forward end upwardly.

Designated at 51 is a bracket member secured to rear wall 12 and carrying at its forward end portion a slotted plate element 52 which underlies and is transverse to bar member 26. The slot in said plate element is designated at 53 and the walls of said slot are formed with longitudinal grooves 54. Designated at 55 is a first wedge

block slidably positioned in slot 53 and rising adjacent the periphery of ratchet wheel 25. A transverse pin 56 passes through the lower portion of block 55 and is slidably engaged in the grooves 54 in the slot walls. Designated at 57 is a second wedge block slidably positioned in said slot 53. A transverse pin 58 passes through the lower portion of block 57 and is slidably engaged in the grooves 54. A spring 59 connects wedge block 55 to wedge block 57 and urges said blocks toward each other. The top end portion of arm 50 projects upwardly through slot 53 and between the wedge blocks 55 and 57. The wedge blocks are shouldered, as shown at 60 and 61, so that the shoulders cooperate with the top surface of plate element 52 adjacent slot 53 to prevent rotation of the wedge blocks around the respective retaining pins 56 and 58. A spring 62 connects wedge block 55 to a pin 63 on plate element 52 and biases said wedge block 55 into engagement with the upper end portion of arm 50.

The upper end portion of arm 50 is formed at its left side, as viewed in Figure 3, with a cam shoulder 64 which is cooperable with wedge block 55 to move said wedge block into locking engagement with ratchet wheel 25 responsive to upward movement of arm 50. Wedge block 57 carries at its right hand corner portion, as viewed in Figure 3, a spring-pressed dog element 65 which is engageable with the ratchet teeth 35 of bar member 26 responsive to movement of wedge block 57 toward the right, as viewed in Figure 3. The right side of the upper end portion of arm 50 is formed with a cam shoulder 66, above the position of cam shoulder 64, which is engageable with wedge block 57 to move said wedge block into a position wherein dog 65 engages ratchet teeth 35 responsive to upward movement of arm 50. The right side of arm 50 is formed with a second cam shoulder 67 below the position of cam shoulder 64, which acts through block 57 and flange 33 to move bar member 26 out of engagement with ratchet wheel 25 as upward movement of arm 50 continues.

Each arm 41 is provided with forwardly extending projections 68 opposing bar member 29 and engageable therewith responsive to depression of the associated key. Below the projections 68 on each arm 41 are additional projections 69 engageable with the bar member 29 when the associated key is depressed with the shift key also depressed, as when capital letters are to be formed. The projections 69 extend further forwardly than the projections 68 by the amount corresponding to the proportionate amount of additional spacing required for capital letters as over the spacing required for lower case letters. Where the projections 68 or 69 are on arms 41 associated with narrow letters or with relatively narrow characters, the projections are correspondingly shorter than projections associated with letters or characters of medium width. As will be explained in further detail, the function of these projections is to move the bar member 29 forwardly by a predetermined amount each time a key is struck, the forward movement of said bar member being communicated to the ratchet bar 26, which, as will presently be described, becomes disengaged from ratchet wheel 25 prior to its forward movement, and on its return movement becomes again engaged with said ratchet wheel, and is allowed to return while engaged therewith, into abutment with the rear wall 12. The rotation of ratchet wheel 25 allowed by the return movement of ratchet bar 26

produces the desired longitudinal movement of the typewriter carriage corresponding to the required letter or character spacing.

When a key is struck, its lever 38 depresses bar member 43, which rotates lever 47 counter-clockwise, as viewed in Figure 2. Arm 50 moves upwardly first bringing cam shoulder 66 into abutment with wedge block 57 and moving said wedge block to the right, as viewed in Figure 3, so that dog member 65 becomes engaged with the ratchet teeth 35 of ratchet bar 26. Cam shoulder 64 then engages wedge block 55 and moves block 55 to the left into locking engagement with ratchet wheel 25. Cam 67 then engages wedge block 51 and exerts sufficient force thereon to move ratchet bar 26 laterally so that its main ratchet teeth 36 disengage from the teeth of ratchet wheel 25.

The projection 68 (or projection 69, if the shift key of the typewriter is depressed) carried on the arm 41 of the activated key lever then pushes bar member 29 forwardly for the distance corresponding to the length of the projection, drawing ratchet bar 26 forwardly a similar distance, the dog member 65 yielding in this direction of movement of said ratchet bar. The type bar 42 strikes the platen 18 and arm 50 begins its descent to normal position. Cam shoulder 67 first moves downwardly to release wedge block 57 sufficiently to allow spring 32 to return ratchet bar 26 to a position wherein its main ratchet teeth 36 again engage the teeth of ratchet wheel 25. Cam shoulder 64 then moves downwardly to release wedge block 55 and to allow it to disengage from the ratchet wheel under the biasing force of spring 62. Finally, cam shoulder 66 moves downwardly and releases wedge block 51, whereby the dog member 65 disengages from the ratchet teeth 35 of ratchet bar 26, allowing the spiral spring 24 to rotate shaft 21 and ratchet wheel 25 counter-clockwise, as viewed in Figure 1, until ratchet bar 26 is moved rearwardly into abutment with rear wall 12. This moves the carriage of the typewriter longitudinally through the desired spacing distance.

Designated at 70, 71 and 72 are spacer bars, carried on respective levers 73, 74 and 75 pivoted to the typewriter frame at rod 39. The spacer bar levers have vertical arms 76, each arm carrying a projection 77 engageable with the bar member 29 responsive to the depression of a spacer bar. The projections 77 are of different lengths, corresponding to different desired spacing distances. Thus the intermediate spacer bar 71 may provide a medium spacing distance, the spacer bar 70 may provide double said medium spacing distance, the spacer bar 72 may provide half said medium spacing distance. By actuating suitable spacer bars, it is thus possible to employ any one of the three available opening spacing distances on the printed line. The spacer levers 73, 74 and 75 normally overlie the bar member 43 in the same plane as the key levers 38.

Projections 68, 69 and 77 are proportioned in length in accordance with the circumferential length of the teeth of ratchet wheel 25. The engagement of a projection 68 with bar member 29 allows wheel 25 to rotate through the arc subtended by one tooth thereof, whereas the engagement of a projection 69 or 77 allows the wheel 25 to rotate through an arc subtended by a multiple number of teeth thereof.

Although the mechanism described in the foregoing will provide the required variation in spacing for one particular size of type, the same

mechanism will also operate to provide the same proportionate spacing where a different size of type is substituted for the original size. Thus, if a smaller size of type is substituted for the original type of the machine of Figure 1, the bevel gear 22 is replaced by a proportionately smaller bevel gear having the same size gear teeth. The rack bar 20 is unfastened from its original position and secured in a new position 10 closer to the platen and in meshing engagement with the new bevel gear, as at openings 78 provided in the rack bar supporting frame.

The above described specific embodiment of the invention has been applied to a typewriter 15 wherein the type-arm assembly block is shifted downwardly when capitals are to be printed. In the case of a typewriter wherein the platen is shifted upwardly to print capitals, a suitable connection of bar member 29 to the platen is provided instead of connecting said bar member 20 to the type-arm assembly block 42' of the typewriter, whereby the bar member will be raised or lowered with the platen. Under these conditions, the projections 69 would be located above the projections 68 instead of below. The present invention contemplates application to machines 25 wherein either the type-arm assembly or the platen is shifted.

While there has been described a specific embodiment of a mechanism for providing variation in spacing on a typewriter printed line in accordance with the space requirement of different letters and characters, it will be understood that various modifications with the spirit of the invention may occur to those skilled in the art. 35 Therefore, it is intended that no limitations be placed on the invention except as defined by the scope of the appended claims.

What is claimed is:

1. In a typewriter, a frame, a carriage supported for longitudinal movement on said frame, a platen rotatably supported on said carriage, a plurality of key levers pivoted to said frame for rotation in transverse vertical planes, forwardly extending projections carried by said levers, said projections varying in length, a longitudinal bar member resiliently secured to said frame forwardly adjacent said projections, rotary means biasing the carriage longitudinally, releasable locking means engaging said biasing means and movable with said bar member, and means actuated by the depression of a key lever for moving said locking means out of engagement with said biasing means, holding the biasing means against movement, and returning the locking means into engagement with the biasing means in a predetermined forwardly advanced position.
2. In a typewriter, a frame, a carriage supported for longitudinal movement on said frame, 60 a platen rotatably supported on said carriage, a plurality of key levers pivoted to said frame for rotation in transverse vertical planes, forwardly extending projections carried by said levers, said projections varying in length, a longitudinal bar member resiliently secured to said frame forwardly adjacent said projections, rotary biasing means urging the carriage longitudinally and including a toothed disc member, an escapement bar movably connected to said bar member and normally engaging with said disc member, and means actuated by the depression of a key lever for moving said escapement bar out of engagement with said disc member while holding the disc member stationary, and returning the escapement bar into engagement with said

disc member in a forwardly advanced position determined by the length of the projection carried on the depressed key lever.

3. In a typewriter, a frame, a carriage supported for longitudinal movement on said frame, a platen rotatably supported on said carriage, a plurality of levers pivoted to said frame for rotation in transverse vertical planes, forwardly extending projections carried by said levers, said projections varying in length, a longitudinal bar member movably secured to said frame forwardly adjacent said projections, spring means biasing the bar member rearwardly, rotary biasing means urging the carriage longitudinally, a toothed disc member carried by said rotary biasing means, an escapement bar movably connected to said bar member and normally interlocking with said disc member, stop means limiting rearward movement of said escapement bar, and means actuated by the depression of any one of said levers for moving the escapement bar out of engagement with the disc member while holding the disc member stationary, and returning the escapement bar into interlocking engagement with said disc member in a forwardly advanced position determined by the length of the projection carried on the lever.

4. In a typewriter, a frame, a carriage supported for longitudinal movement on said frame, a platen rotatably supported on said carriage, a plurality of levers pivoted to said frame for rotation in transverse vertical planes, forwardly extending projections carried by said levers, said projections varying in length, a longitudinal bar member movably secured to said frame forwardly adjacent said projections, spring means biasing said bar member rearwardly, rotary biasing means urging the carriage longitudinally, a toothed disc member carried by said rotary biasing means, an escapement bar pivotally connected to said bar member, spring means biasing said escapement bar into interlocking engagement

with the periphery of said disc member, stop means limiting rearward axial movement of said escapement bar, and means actuated by the depression of any one of said levers for sequentially locking the disc member, moving the escapement bar out of engagement with said disc member, returning the escapement bar in a forwardly advanced position into interlocking engagement with said disc member, and then unlocking the disc member.

5. In a typewriter, a frame, a carriage supported for longitudinal movement on said frame, a platen rotatably supported on said carriage, a plurality of levers pivoted to said frame, means biasing the levers upwardly, projections carried by said levers, said projections varying in length, a longitudinal bar member resiliently secured to said frame adjacent said projections, rotary biasing means urging said carriage longitudinally, a ratchet disc carried by said rotary biasing means, a ratchet bar pivotally connected to said bar member, spring means biasing said ratchet bar into engagement with said ratchet disc, and movable cam means actuated responsive to the depression of any one of said levers and its subsequent return to normal position for sequentially locking the ratchet disc, moving the ratchet bar out of engagement therewith, returning the ratchet bar into engagement with the disc in an advanced position, and then unlocking the disc.
